Inventor,

George A. Burnham

Atty

UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRIC SWITCH.

Application filed July 25, 1921. Serial No. 487,221.

This invention relates to oil immersed electric switches of the type characterized by having a relatively yieldingly connected or supported oil receptacle and switch frame; and as set forth in my co-pending application Serial No. 309,853, filed July 10, 1919, which application has eventuated in Patent No. 1,413,156, dated April 18, 1922.

For certain purposes it is preferable to employ a fixed switch frame and a yieldingly-supported movable oil receptacle; and such a type is illustrated in said co-pending application; and for other purposes it is preferable to employ a fixed oil receptacle and a movable switch frame yieldingly disposed with relation to the oil receptacle; and such a switch is typified in a removable-unit cell-type switch.

The current carried by a switch of the latter type may be considerable and the circuit leads or bus bars to which the stationary switch-members are adapted to be connected are relatively massive and rigid members and, furthermore, are rigidly supported by fixed insulators secured to stationary supports. The stationary switch members are carried by the yieldingly-supported movable frame and consequently have a movement relative to the rigidly-supported circuit leads or bus-bars. With the usual type of connection between the switch-members and circuit leads or bus-bars, both are rigidly united, with the result that either the bus-bars may restrain the frame from yielding to relieve the strain on the switch due to a gaseous pressure rise within the switch resulting from interrupting the circuit under load, or the bus-bars may be torn from their supports when the circuit is interrupted and the switch frame is moved upward against its yielding supporting-means.

An object of this invention is to provide the combination of an electric switch having a yieldingly-supported movable switch frame bearing the stationary switch-members, stationarily-secured rigid bus-bars and flexible means yieldingly connecting said switch-members and bus-bars electrically whereby to absorb the movement of said switch-members and permit a movement of

said switch frame and switch-members independently of said bus-bars.

A further object is generally to improve the construction and operation of an electric switch.

Fig. 1 is a side elevation of a removable unit, cell-type switch selected to illustrate the invention.

Fig. 2 is a sectional detail of the switch of Fig. 1 with the switch frame in a vertically displaced position and illustrating the manner in which the flexible connectors absorb the movement of the switch-members without transmitting the movement to the stationarily-supported bus-bars.

Fig. 3 is a diagrammatic detail illustrating the invention applied to the combination of the switch of Fig. 1 and horizontally-arranged, stationarily-supported bus-bars.

Fig. 4 is a perspective view of a flexible connector.

As here shown, the switch embodying the invention is disposed in a cell A. The switch comprises the fixed oil receptacle 10 mounted on the carriage 11 by which the switch, when disconnected from the stationarily-supported bus-bars may be moved as a unit from the cell. A frame 12, comprising a cover for the oil receptacle, is disposed over the top of the oil receptacle and is yieldingly secured thereon by the bolts 13 carried by the oil receptacle and the helical springs 14 disposed over said bolts and engaging lugs 15 of said frame. Said frame may be removed from the oil receptacle by first removing the nuts 16 threaded removably on the ends of said bolts; and the tension of said springs, and, therefore, the movement of said frame, may be governed by an obvious adjustment of said bolts. The switch may be vented downwardly through the peripheral passage 17 between the flange 12^a of the switch frame and the side wall of the oil receptacle.

Due to the opening of the switch under load a considerable gaseous pressure may be created in the expansion space B above the oil in the oil receptacle and under the switch frame, and said switch frame will be moved upwardly against the springs 14 by said pressure to increase the volume of

said expansion space and keep down the internal pressure and reduce stresses on the bolts 13 while the pressure is being relieved by a discharge of gas and vapor 5 through the vent passage 17.

A movable switch member 20 is disposed within said oil receptacle and is dependingly secured to switch-operating mechanism 21, here shown as carried by said switch frame 10 although it may be supported otherwise in any desirable manner. Stationary switch-members 22 are secured rigidly to the switch frame and are movable therewith in response to pressure conditions within the 15 switch.

In the cell-type switch illustrated in Fig. 1 the rigid circuit leads or bus-bars 23 are secured immovably in insulators 24 carried by the stationary top wall 18 of the cell A.

20 With a fixed or stationarily-supported switch frame the connectors extended between said bus-bars and the stationary switch members are rigid and inflexible members. In accordance with the invention, I employ flexible means to connect said bus-bars and switch-members electrically whereby to admit of the vertical movement of said switch frame relative to said bus-bars in response to pressure conditions within the switch.

25 Said flexible means may comprise the flexible connectors 25; and said connectors may each comprise one or a plurality of flexible strips 26 united at their ends by suitable means, as by solder, but otherwise preferably unconnected, at least for the major portion of their length, whereby each strip may flex and bend and absorb the motion of said switch frame and stationary switch members independently of other strips of

30 the connector. Each strip may be spaced from adjacent strips by the spacer blocks 27 and 28 if desired, to enhance the freedom of movement of each strip; and said spacer blocks may also serve to provide relatively 35 massive terminals for the connector. The number of strips may vary, as may also the dimensions of the strips, but preferably the strips are relatively thin, for flexibility and broad whereby to radiate heat the more effectively. The terminals of said connectors 40 may be provided with bolt-holes 29 and said connectors may be secured removably to said bus-bars and stationary switch-members by the bolts 30. The length of said connectors is preferably substantially greater 45 than the distance between the stationarily-supported bus-bars and stationary switch-members in the normal, which will be the lowest, position of the switch frame; and

50 the flexible connectors will thereby assume a sinuous shape, as illustrated, whereby to enhance the flexibility of the connectors.

It will be apparent that, with the construction above set forth, the switch frame and stationary switch-members may move

upward in response to pressure conditions within the switch, and return to normal position without putting strain on, or tendency to move, the stationarily-supported bus-bars, and the movement of the switch frame and switch-members will be absorbed in the flexible connectors. 70

When the switch is to be removed from the cell the flexible connectors will be first detached from the stationary switch-members by removing the connecting bolts 30. 75

In Fig. 3 the stationarily-supported rigid bus-bars 23^a are horizontally-arranged instead of vertically-arranged as in Fig. 1, and are stationarily-supported on the 80 rigidly fixed insulators 24^a above the switch frame and are connected to the switch-members 22 by the flexible connectors 25 as in Fig. 1.

In addition to the movement-absorbing 85 properties of said flexible connectors, they have the further advantage of facilitating the connecting of the switch to the bus-bars since the flexibility of the strips may permit a substantial lack of alignment between the 90 switch-members and bus-bars and yet secure satisfactory electrical connection and the functioning of the connectors to absorb the movement of the switch-members.

The switch operating mechanism 21 is 95 here shown as carried by the movable switch frame 12 and operated by the electrically-controlled mechanism 35 disposed upon the top wall 18 of the cell by the vertically-movable rod 36 which is connected removably to the operating mechanism by the bolts 37. When the switch is to be removed from the cell the rod 36 will be disconnected from the operating mechanism by removing the bolts 37 as is usual practice with this type 100 of switch.

The switch operating mechanism specifically includes the lever 21^a pivoted at one end to the switch frame 12 and bearing the movable switch-member 20 at the other end. 110 A lever 21^b is also pivoted to said switch frame and is loosely connected to the rod 21^c; and said rod is connected to the rod 36 of the electrically-controlled mechanism 35. A link 21^d is pivotally connected with said lever 21^a and said lever 21^b. Said mechanism is so arranged that an upward movement of said rod 21^c operates to move said movable switch-member 20 upwardly to close the switch, and a downward movement of said rod operates to open the switch. 115

It will be noted that, as the switch-operating mechanism is carried by the movable switch frame and the rod 21^c thereof is connected to the stationarily-supported electrically-controlled mechanism 35, when said switch frame is moved upward in response to pressure conditions within the switch due to the separation of the stationary and movable switch-members, it will operate on the 120 125 130

switch-operating mechanism to move the movable switch-member 20 toward open position and accelerate the switch-opening movement thereby to provide for a more

5 rapid interruption of the circuit and thereby reduce the gaseous pressure rise and increase the interrupting capacity of the switch than would otherwise be the case.

10 The invention may be embodied in other combinations than herein set forth without departing from the spirit thereof.

I claim:

1. An electric switch having a stationary oil receptacle, a switch frame comprising a 15 cover for said oil receptacle movable thereon in response to pressure conditions within the switch, stationary and movable switch members immersed in the oil in said oil receptacle, switch operating mechanism connected 20 with the movable switch member and cover, and means having a connection with said operating mechanism whereby the upward

movement of said switch frame above said oil receptacle operates to accelerate the speed of opening movement of the movable switch- 25 member.

2. An electric switch having means to accelerate the opening movement of the switch comprising the combination of a stationary oil receptacle, a switch-frame comprising a 30 cover for said receptacle movable thereon in response to pressure conditions within the switch, stationary switch-members carried by said frame, a movable switch-member and switch-operating mechanism carried by said 35 frame, stationarily-supported controlling-mechanism for said operating mechanism, and an operating rod extended between and connecting said controlling and operating mechanisms. 40

In testimony whereof, I have signed my name to this specification.

GEORGE A. BURNHAM.
